(57) **CLAIM**

The ornamental design for a packaging container for produce, as shown and described.

DESCRIPTION

FIG. 1 is a top, front, and right side perspective view of a packaging container for produce in accordance with the present invention;

FIG. 2 is a bottom, rear, and left side perspective view of the packaging container for produce of FIG. 1;

FIG. 3 is a front elevational view of the packaging container for produce of FIG. 1;

FIG. 4 is a rear elevational view of the packaging container for produce of FIG. 1;

FIG. 5 is a left side elevational view of the packaging container for produce of FIG. 1;

FIG. 6 is a right side elevational view of the packaging container for produce of FIG. 1;

FIG. 7 is a top plan view of the packaging container for produce of FIG. 1;

FIG. 8 is a bottom plan view of the packaging container for produce of FIG. 1; and,

FIG. 9 is a cross-sectional view of the packaging container for produce of FIG. 1, taken along line 9-9 in FIG. 7.

1 Claim, 7 Drawing Sheets
